Primary Examiner — Carla J Wright

(57) **CLAIM**

The ornamental design for a phone case as shown and described.

DESCRIPTION

FIG. 1 is a rear, left and bottom perspective view of a phone case showing our new design;

FIG. 2 is a front, right and bottom perspective view thereof; FIG. 3 is a rear view thereof;

FIG. 4 is a front view thereof;

FIG. 5 is a left view thereof;

FIG. 6 is a right view thereof;

FIG. 7 is a top view thereof; and,

FIG. 8 is a bottom view thereof.

The broken lines in the drawing figures form no part of the claimed design, and they depict portions of the phone case that form no part of the claimed design.

1 Claim, 8 Drawing Sheets
